SUPPORTING STAND FOR TABLES, BASINS, AND THE LIKE

Ted E. Cooke, Seattle, Wash.

Application November 23, 1948 Serial No. 61,698

This invention relates to a supporting stand for tables, basins, and the like, and, more particularly, is an improvement in a corner construction for multi-legged stands that may be partially preassembled and delivered to the point of use in a collapsed condition for erection when desired.

Among the important objects of this invention are: to provide a novel, partially assembled but collapsed stand that is extremely compact; to provide a corner construction that permits partial preassembly to a collapsed state but may be readily erected into a stiff and sturdy condition with ease and simplicity; to provide a construction for such a stand that is simple and inexpensive to produce; and to provide a stand that may be formed of standard metallic shapes of light weight material but which can be knocked down and will withstand rough handling without breakage and distortion in its partially preassembled and collapsed form and will serve adequately for its intended purpose during a long and useful life.

Other objects and advantages of the invention will be apparent during the course of the following description.

In the accompanying drawing, forming a part of this specification, like numerals are employed to designate like parts throughout. Among the various views of the drawing.

Figure 1 is a perspective view of an erect stand containing my corner construction:

Figure 2 is an enlarged partially assembled perspective view of the elements forming the corner construction of my supporting stand;

Figure 3 is a fragmentary elevation view in the plane 3-3 of Figure 2 showing the locking of the interlocking means employed in joining parts of my corner construction; and

Figure 4 is a detail perspective view showing an alternate manner of interlocking means useful in my corner construction.

A particular use of my invention lies in the manufacture of stands for use in homes and apartment buildings and the like for supporting laundry trays. Having that in mind I have shown in Figure 1, in phantom, such a double tray element 10 which is usually formed of ceramic materials and has considerable weight and bulk. Such trays weigh about four hundred pounds. This showing is for the purpose of exemplification and is not intended to limit my invention since it will be obvious that the construction shown in Figure 1 will also serve to support a low table or bench and, by altering proportions as to height or length, other objects.

Laundry stands are usually manufactured of rough materials and preferably are partially assembled to knock-down condition at a factory for transportation and delivery to the point of use in the most compact form. They travel by railroad and truck, are roughly handled in transit, and, when they are to be used, are usually set up by plumber's helpers and other relatively unskilled mechanics. When they are erected it is always desirable that they be rigid and rugged and not involve a great multiplicity of parts such as braces and the like that will limit access to under the laundry trays.

15 It is with these and other objects more fully stated herein that I have arranged my stand to comprise the several upright leg elements 12, 13, 14, and 15 in the rectangular form shown in Figure 1. These leg elements are formed of angle-iron pieces and are arranged in the stand so that the two outer faces of the angles of the leg elements form the corners of the stand and the groove between the webs of the angle-iron faces inwardly. In the preferred form of the invention shown in Figure 2 a pair of upwardly open notches 16, 17 are formed, one in each web of the 20 leg element.

Between leg element 12, to a first side thereof, and leg element 13 I provide the horizontal first rail 18 which has pins 19 and 20 outstanding on its inner face, one said pin being at each end of the rail. Pin 19 slips into notch 16 to form a connection for maintaining the rail 18 in horizontal and right-angular relation to the legs 12 and 13. Brace bars 22, 23 diagonally between leg 12 and rail 18 and leg 13 and rail 18 serve to stiffen the stand when it is assembled. The brace bars are non-separably connected at each end by rivets 24 which permit pivotal movement of the brace bar relative either the leg element or rail for a purpose later to be described.

40 Between leg element 12, to a second side thereof, and leg element 15 I provide a similar rail 26 having a pin 27 which fits into notch 17 and another brace bar 28 joined by pivotal rivets 29 to the rail 26 and leg element 12.

45 In like manner rail 26 joins leg element 15, and rail elements 30 and 32 extend between the pairs of leg elements 15 and 14, and 13 and 14, respectively. Also similar brace bars are employed on the diagonal in the finished and assembled stand to impart rigidity. Each rail joins a leg element with the pin and notch connection previously described and the braces are all joined to the legs or rails with set rivets that nevertheless permit swinging of the braces, rails and leg elements 50 about the axes of the rivets.

When it is desired to secure a pin into a notch, referring to Figure 3, pressure is applied against the free wall of the notch of the leg element in the direction indicated by the arrow and the same is distorted and turned over the pin as shown, to prevent its upward withdrawal from the notch. This is usually the last step in the final assembly of the stand.

Alternately to the pin and notch arrangement described, I may employ the arrangement of Figure 4 in which the notch 43 is formed on the rail 40 and the pin 41 is carried by the leg element 42. In this case, the outer end of the rail forming a wall of the notch 43 is bent over the pin to prevent dislodgment.

As the stands are manufactured and being assembled all the parts are brought together with the braces, such as 22 and 28, joining between the leg element 12 or 13, 14 or 15, as the case may be and the first rail 18, or the second rail 26, respectively, but without the pins being seated in the notches. In such condition the legs may be placed in alignment with the longer side rails, whereupon the shorter side rails may be brought into overlying relation to the longer side rails and the whole assembly brought together into a tight bundle-like condition that is compact, may be handled roughly, and will pack most economically during shipment and storage. Since the parts are joined together throughout the 30 bundle by the brace bars and rivets none may become displaced and yet the stand may not be racked or damaged easily as is the case with a more fully assembled frame.

At such time as erection of the stand is to take 35 place, the leg elements are brought into upright position with the rails horizontally placed and the pin and notch connections effected as shown in Figure 1. When the parts are all properly trued up the operator usually sets the walls of the notches about the pins and the stand is ready to use.

Such a stand, used to support a table or bench, has considerable resistance to racking and wobbliness and may be otherwise used for a multitude of purposes.

Having thus shown and described my invention, I claim:

1. A corner construction for collapsed, multi-legged supporting stands for supporting tables, basins and the like, comprising: a metallic leg element having a generally L-shaped cross section to be positioned upright; a first metallic bar rail to extend from a first flange of said leg element to a similar leg element to said side; a second metallic bar rail independent of and disconnected from said first rail to extend from a second flange of said leg element to another similar leg element to said side, said rails extending from said leg element at right angles to each other; between said leg element and said first rail a first brace bar pivotally attached to each member; between said leg element and said second rail a second brace bar pivotally attached to each member; and between each said first and second rail a flange of and the leg element means forming a pin and notch connection for securing the rails in right angular relationship to each other and to the leg element when the corner construction is erected to supporting condition.

2. A corner construction according to claim 1, in which the notch of the pin and notch connection between each rail and leg element is of sufficient depth that a wall forming one side of said notch may be deflected to partially close the notch about the pin when the latter is positioned therein.

3. A corner construction according to claim 1, in which the notch of the pin and notch connection is open upwardly and is located in a flange of the leg element and the interfitting pin of said connection is mounted on the rail.

TED E. COOKE.
